(57) **CLAIM**

The ornamental design for an autonomous industrial robot as shown and described.

DESCRIPTION

FIG. 1 is a front, right perspective view of a first embodiment of the industrial robot;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof;

FIG. 7 is a bottom plan view thereof;

FIG. 8 is a front, left perspective view thereof;

FIG. 9 is a detail view of the area enclosed by the box 9 in FIG. 1;

FIG. 10 is a cross-sectional view taken along 10-10 in FIG. 6;

FIG. 11 is a front, right perspective view of a second embodiment of the industrial robot;

FIG. 12 is a front elevational view thereof;

FIG. 13 is a rear elevational view thereof;

FIG. 14 is a left-side elevational view thereof;

FIG. 15 is a right-side elevational view thereof;

FIG. 16 is a top plan view thereof;

FIG. 17 is a bottom plan view thereof;

FIG. 18 is a front, left perspective view thereof;

FIG. 19 is a detail view of the area enclosed by the box 19 in FIG. 11;

FIG. 20 is a cross-sectional view taken along 20-20 in FIG. 16;

FIG. 21 is a front, right perspective view of a third embodiment of the industrial robot;

FIG. 22 is a front elevational view thereof;

FIG. 23 is a rear elevational view thereof;

(Continued)

FIG. 24 is a left-side elevational view thereof;
 FIG. 25 is a right-side elevational view thereof;
 FIG. 26 is a top plan view thereof;
 FIG. 27 is a bottom plan view thereof;
 FIG. 28 is a front, left perspective view thereof;
 FIG. 29 is a detail view of the area enclosed by the box 29 in FIG. 21; and,
 FIG. 30 is a cross-sectional view taken along 30-30 in FIG. 26.
 The evenly spaced broken lines depict parts of the industrial robot that form no part of the claimed design.
